UNITED STATES PATENT OFFICE.

OLIE L. ERION AND LEONARD A. PICK, OF COLUMBUS, OHIO.

CONE-GRAVE STOKER.

Application filed June 20, 1927. Serial No. 200,101.

The present invention has reference to grate construction and aims to provide a novel form of grate of the cone type so constructed that fuel deposited at the top of the grate may gravitate to the bottom thereof, while the fuel is being burned.

Another object of the invention is to provide a grate including a plurality of superposed corrugated ring members graduated in size and arranged in spaced relation with each other to provide air spaces so that a draft of air may pass through the grate to insure proper combustion of the fuel.

A still further object of the invention is to provide a shaking ring at the base of the grate, the ring being of a diameter greater than the diameter of the grate proper to receive material from the grate.

A further object of the invention is the provision of means for stoking the grate and simultaneously operating the shaking ring, thereby preventing the fuel from clogging on the grate.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a longitudinal sectional view through a firebox of a furnace illustrating grate and stoker constructed in accordance with the invention.

Figure 2 is a bottom view of the grate.

Figure 3 is a front elevational view thereof.

Figure 4 is an enlarged detail view illustrating the supporting arms on which the shaking ring operates.

Referring to the drawings in detail, the reference character 5 designates the outer casing of the furnace, and the reference character 6 indicates the lining or body portion of the furnace.

The grate forming the essence of the present invention embodies a plurality of superposed spaced corrugated ring members 7, the ring members being supported by means of the arms 8, which arms are carried by the bearing rings 9, the arms 8 being of

various lengths so that portions of the rings extend beyond the peripheries of their adjacent upper rings defining shelves so that material may collect thereon. These arms 8 contact with the adjacent lower ring members to the end that the ring members 7 are held in spaced relation with each other, allowing air to pass through the cone-shaped grate.

At the base of the grate proper is a shaking ring 10 which rests on the brackets 11 and 12 the bracket 11 being formed integral with the feed pipe 13, while the brackets 12 are secured to the inner surface of the member 6.

Surrounding the inner end of the feed pipe 13 is a curved stoker pipe 14 formed with an enlargement 15 defining a shoulder to receive the weight of the ring members 7, the lowermost bearing ring being shown as resting directly on the shoulder.

Formed in the shaking ring are a plurality of openings 16, which openings permit the ashes from the burned fuel to pass through the shaking ring and into the ash-pit directly thereunder. A horizontal shaft indicated at 17 extends through the feed pipe 13 and stoker pipe 14, the shaft having a head 18 formed on its inner end, the head being supplied with a pin 19 eccentrically mounted on the head, the pin providing means whereby the connecting link 20 may be connected to the shaft 17.

The upper end of the link 20 connects with the shaking ring 10 through the member 21 that has pivotal connection with the link 20 and which has an extension 22 supplied with a nut 23 for securing the member 21 to the shaking ring 10, after the extension 22 has been passed through one of the openings 16 of the shaking ring. It will thus be seen that the movement of the link and shaking ring 10 may be adjusted or varied, by merely changing the position of the extension 22 by placing the extension 22 in one of the adjacent openings of the shaking ring and substituting a longer or shorter link 20.

Operating in the pipe 13 is a worm 24 that is mounted on the shaft 17, the worm acting to feed material to the stoker pipe 14. As shown by Figure 1, the feed pipe 13 is formed with an opening 25 through which fuel, which may be in the form of coke, coal or the like, passes to the feed pipe 13.

Arranged above the pipe 13 and communicating therewith is a delivery pipe 26

through which fuel passes to the feed pipe 13. An agitator 27 operates in the pipe 26 loosening the material in the pipe 26 and preventing the material from clogging on its passage to the pipe 13.

10 A sprocket wheel indicated at 28 is mounted on the forward end of the shaft 17 and transmits movement to the shaft 29 through the sprocket wheel 30 and chain 31 operating over the sprocket wheels 28 and 30. A power chain 32 from a suitable power device not shown, operates over sprocket wheel 33 secured to the shaft 17 to operate the worm and simultaneously operate the shaking ring.

15 In order that the shaft 17 may, if desired, be operated by manual power, a crank 34 is provided which crank is secured at the forward end of the shaft 17 as shown by Figure 1.

20 From the foregoing it will be seen that fuel may be fed upwardly through the cone-shaped grate, when the shaft 17 is operated to cause the worm 24 to force the material or fuel fed into the feed pipe through the pipe 14. It will also be noted that the fuel passing from the pipe 14 collects at the top of the grate and falls by gravity over

the several corrugated ring members where it is burned, the ashes falling onto the shaking ring 10, which moves back and forth under the action of the shaft 17 and link 20.

We claim:

In combination with a furnace, a stoker pipe therein, directed upward and having an external shoulder, bearing rings mounted on said pipe with the lowest ring resting on said shoulder, each said ring being provided with radial arms, corrugated grate rings surrounding said pipe and supported in stepped relation by said arms, a shaking ring arranged below the lowest grate ring and in stepped relation thereto, a feed pipe communicating with the stoker pipe, a shaft extending axially through the feed pipe and through the lower end of the stoker pipe, a spiral vane on the shaft for forcing fuel through said pipe onto the grate and means for transmitting motion from the shaft to the shaking ring.

In testimony that we claim the foregoing as our own, we have hereto affixed our signatures.

OLLIE L. ERION.
LEONARD A. PICK.
